DESIGN FOR A COVER FOR HOT WATER BOTTLE

Annabell Culverwell, New York, N. Y.

Application May 4, 1938, Serial No. 76,973

Term of patent 7 years

To all whom it may concern:

Be it known that I, Annabell Culverwell, a citizen of the United States, residing at 342 West 71st St., in the city, county, and State of New York, have invented a new, original, and ornamental Design for a Cover for Hot Water Bottle, of which the following is a specification, reference being had to the accompanying drawing, forming part thereof, and in which:

for hot water bottles, showing my new design with the cover in open position.

I claim:

The ornamental design for a cover for hot water bottle, as shown and described.

ANNABELL CULVERWELL.
